ABSTRACT

A cutting assembly for a mining machine includes a mount configured to move about a first axis relative to a chassis of the mining machine and a ranging arm coupled to the mount. The ranging arm is moveable relative to the mount. The cutting assembly includes a cutting head having a housing coupled to the ranging arm. The housing is moveable relative to the ranging arm. The cutting head includes a drum supported for rotation relative to the housing about a rotational axis, a plurality of cutting bits coupled to the drum, and at least one motor supported by the housing to drive the drum about the rotational axis.

CUTTING ASSEMBLY FOR LONGWALL MINING SYSTEM

CROSS-REFERENCE TO RELATED APPLICATION

This application claims the benefit of U.S. Provisional Patent Application No. 63/114,235 filed Nov. 16, 2020, the contents of which are incorporated herein by reference.

TECHNICAL FIELD

The present disclosure relates to longwall mining systems, and particularly to cutting assemblies for a longwall mining system.

SUMMARY

Mining systems, such as longwall mining systems, include one or more ranging arms having cutting drums for cutting material from a mine face. In some embodiments, the material is deposited on an armored face conveyor (AFC) and carried away from the mine face.

In one aspect, a cutting assembly for a mining machine includes a mount configured to move about a first axis relative to a chassis of the mining machine and a ranging arm coupled to the mount. The ranging arm is moveable relative to the mount. The cutting assembly includes a cutting head having a housing coupled to the ranging arm. The housing is moveable relative to the ranging arm. The cutting head includes a drum supported for rotation relative to the housing about a rotational axis, a plurality of cutting bits coupled to the drum, and at least one motor supported by the housing to drive the drum about the rotational axis.

In another aspect, a cutting assembly for a mining machine includes a mount configured to move about a first axis relative to a chassis of the mining machine and a cutting head having a housing, a drum rotatably coupled to the housing about a rotational axis, a plurality of cutting bits coupled to the drum, and at least one motor supported by the housing to drive the drum about the rotational axis. The cutting assembly includes a ranging arm coupled to the mount and supporting the cutting head for movement about the first axis.

In yet another aspect, a cutting assembly for a mining machine includes a ranging arm configured to be coupled to a chassis of the mining machine and a cutting head having a housing coupled to the ranging arm, a drum rotatably coupled to the housing about a rotational axis, a plurality of cutting bits coupled to the drum, and at least one motor supported by the housing to drive the drum about the rotational axis. The cutting assembly is configured to include at least four degrees of movement of the drum relative to the chassis.

Other aspects will become apparent by consideration of the detailed description and accompanying drawings.

BRIEF DESCRIPTION OF THE DRAWINGS

FIG. 1 is a perspective view of a mining machine including cutting assemblies.

FIG. 2 is a perspective view of a cutting assembly according to one embodiment.

FIG. 3 is a perspective view of a powertrain that drives a cutting drum of the cutting assembly of FIG. 2.

FIG. 4 is a perspective view of a housing of the powertrain of FIG. 3.

FIG. 5 is a first exploded view of the powertrain of FIG. 3.

FIG. 6 is a second exploded view of the powertrain of FIG. 3.

FIG. 7 is a cross sectional view of the powertrain taken along line 7-7 of FIG. 3.

FIG. 8 illustrates a side view of the mining machine of FIG. 1 during operation.

FIG. 9 is a first perspective view of a cutting assembly according to another embodiment.

FIG. 10 is a second perspective view of the cutting assembly of FIG. 9.

FIG. 11 is a side view of the cutting assembly of FIG. 9 illustrating a first range of motion of the cutting assembly.

FIG. 12 is a top view of the cutting assembly of FIG. 9 illustrating a second range of motion of the cutting assembly.

FIG. 13 is a top view of the cutting assembly of FIG. 9 illustrating a third range of motion of the cutting assembly.

FIG. 14 is a top view of the mining machine of FIG. 1 during operation including the cutting assemblies of FIG. 9.

FIG. 15 is a perspective view of a cutting assembly according to another embodiment.

FIG. 16 is a perspective view of a portion of the cutting assembly of FIG. 15.

FIG. 17 is a cross sectional view of the cutting assembly taken along line 17-17 of FIG. 15.

FIG. 18 is a top view of the cutting assembly of FIG. 15 illustrating a first range of motion of the cutting assembly.

FIG. 19 is a top view of the cutting assembly of FIG. 15 illustrating a second range of motion of the cutting assembly.

FIG. 20 is a perspective view of a cutting assembly according to another embodiment.

FIG. 21 is a perspective view of a portion of the cutting assembly of FIG. 20.

FIG. 22 is a top view of the cutting assembly of FIG. 20 illustrating a first range of motion of the cutting assembly.

FIG. 23 is a side view of the cutting assembly of FIG. 20 illustrating a second range of motion of the cutting assembly.

FIG. 24 is a perspective view of a powertrain according to another embodiment that drives a cutting drum of a cutting assembly.

FIG. 25 is a cross sectional view of the powertrain taken along line 25-25 of FIG. 24.

DETAILED DESCRIPTION

Before any embodiments are explained in detail, it is to be understood that the disclosure is not limited in its application to the details of construction and the arrangement of components set forth in the following description or illustrated in the following drawings. The disclosure is capable of supporting other embodiments and being practiced or being carried out in various ways. Also, it is to be understood that the phraseology and terminology used herein is for the purpose of description and should not be regarded as limiting. Use of "including" and "comprising" and variations thereof as used herein is meant to encompass the items listed thereafter and equivalents thereof as well as additional items. Use of "consisting of" and variations thereof as used herein is meant to encompass only the items listed thereafter and equivalents thereof. Unless specified or limited otherwise, the terms "mounted," "connected," "supported," and "coupled" and variations thereof are used broadly and encompass both direct and indirect mountings, connections, supports, and couplings. Terms of degree, such as "substantially," "about," "approximately," etc. are understood by those of ordinary skill to refer to reasonable ranges outside

of the given value, for example, general tolerances associated with manufacturing, assembly, and use of the described embodiments.

FIG. 1 illustrates a mining machine, such as a longwall shearer 10, including a pair of cutting assemblies 15 each pivotably coupled to a frame or chassis 20 about a first axis 25. The chassis 20 includes a power unit 30 (e.g., electrical power unit, hydraulic power unit, combination of electrical and hydraulic power unit, etc.) operable to move or tram the shearer 10 along a track 35 in a first direction 40 or a second direction 45 opposite the first direction 40.

FIG. 2 illustrates one cutting assembly 15 that includes substantially the same components as the other cutting assembly 15. As such, only the first cutting assembly 15 will be described in detail, but the components and features of the first cutting assembly 15 are equally applicable to the second cutting assembly 15. The illustrated cutting assembly 15 includes a chassis mount 50, a drum and motor assembly 55 (e.g., a cutting head), and a support structure 60 (e.g., a ranging arm) coupling the drum and motor assembly 55 to the chassis mount 50. The chassis mount 50 is pivotably coupled to the chassis (e.g., at an end portion 65) about the first axis 25. A hydraulic actuator (not shown), which is powered by the power unit 30, is coupled to the chassis 20 and the chassis mount 50 and operable to pivot the cutting assembly 15 about the first axis 25.

With continued reference to FIG. 2, the chassis mount 50 is fixed to an inboard end 70 of the support structure 60. The illustrated support structure 60 includes a plurality of structural members 75. In some embodiments, the structural members 75 can be hollow cuboid tubes coupled together (e.g., by a welding process, etc.) to provide an engineered support structure (support arm) that supports the weight of the drum and motor assembly 55 in a cantilevered manner relative to the chassis mount 50. In other embodiments, the structural members 75 can be hollow cylindrical tubes, solid cuboid members, solid cylindrical members, etc.

As shown in FIGS. 2 and 3, the drum and motor assembly 55 includes a powertrain 80 supported by a housing 85 and operable to drive a drum 90 about a rotational axis 95. The drum 90 includes a plurality of cutting bit assemblies 100. The illustrated housing 85 is coupled to an outboard end 110 of the support structure 60 opposite the inboard end 70. The housing 85 includes a plurality of cavities 115 formed in a rear side 120 of the housing 85. The cavities 115 support a plurality of motors 125 (e.g., electric motors, hydraulic motors, etc.). In the illustrated embodiment, the powertrain 80 includes three electric motors 125 each positioned within one cavity 115. In other embodiments, the powertrain 80 can include one motor 125, two motors 125, or more than three motors 125. The illustrated motors 125 are in communication with the power unit 30 of the chassis 20 for the power unit 30 to drive the motors 125. Accordingly, the illustrated support structure 60 supports power lines (e.g., electrical power lines, hydraulic power lines, etc.) that couple the motors 125 to the power unit 30. The support structure 60 also supports lubricant lines to supply the powertrain 80 with lubricant (e.g., oil). The support structure 60, however, does not provide a housing to support any component of the powertrain 80. Rather, the powertrain 80 is supported by the housing 85.

With reference to FIGS. 4-7, each motor 125 is coupled to an output pinion 140 that is rotatably coupled between a pinion bearing retainer 145, the housing 85, and a central bearing retainer 150. In particular, a first pinion roller bearing 155 is seated within each pinion bearing retainer 145 to rotatably support a first side of the corresponding output

pinion 140 (FIG. 7). Each pinion bearing retainer 145 is fixed to a rear surface 160 of the housing 85. A second pinion roller bearing 165 is coupled between the housing 85 and the central bearing retainer 150 to rotatably support a second side of the corresponding output pinion 140 (FIG. 7). The central bearing retainer 150 is fixed to an inner surface 170 (FIG. 4) of the housing 85. The output pinions 140 are positioned relative to the housing 85 such that a portion of each output pinion 140 extends through a corresponding aperture 175 (FIG. 4) formed in the housing 85 to engage a sun gear 180.

As shown in FIGS. 5-7, the sun gear 180 is rotatably coupled between the housing 85 and the central bearing retainer 150 in a direction along the rotational axis 95. In particular, a first sun gear roller bearing 185 is seated within the housing 85 to rotatably support a first side of the sun gear 180. A second sun gear roller bearing 190 is seated within the central bearing retainer 150 to rotatably support a second side of the sun gear 180. The sun gear 180 includes a central aperture 195 (FIG. 5) that receives a drive shaft 200. The drive shaft 200 is engaged with the sun gear 180 to be driven about the rotational axis 95. As shown in FIG. 7, a lubricant conduit 205 extends through the drive shaft 200 and is operable to dispense lubricant (e.g., oil, etc.) throughout the powertrain 80. The lubricant enters through an inlet 210 formed in the housing 85.

The drive shaft 200 includes a shaft gear 215 engaged with a plurality of first stage planetary gears 220. In the illustrated embodiment, the plurality of first stage planetary gears 220 includes four first stage planetary gears 220. In other embodiments, the plurality of first stage planetary gears 220 can include fewer or more than four first stage planetary gears 220. The illustrated first stage planetary gears 220 are rotatably coupled to a carrier 225. In particular, each first stage planetary gear 220 is coupled to the carrier 225 by a first pin 230 and first planetary roller bearings 235 (FIG. 7) positioned between the first stage planetary gear 220 and the first pin 230. The first pins 230 are fixed to the carrier 225. In other embodiments, each first stage planetary gear 220 can be fixed relative to the corresponding first pin 230 and the first pins 230 can be rotatably coupled to the carrier 225 by the first planetary roller bearings 235. The first stage planetary gears 220 are also engaged with a first ring gear 240 such that the first stage planetary gears 220 are supported between the shaft gear 215 and the first ring gear 240.

The illustrated carrier 225 is coupled to a compound gear 245 that is positioned around the drive shaft 200 without engaging the drive shaft 200 (FIG. 7). The illustrated compound gear 245 includes a first portion 250 that is received within the carrier 225 to be engaged therewith. The compound gear 245 also includes a second portion 255 having a greater outer diameter than the first portion 250. The second portion 255 is engaged with a plurality of second stage planetary gears 260. The second stage planetary gears 260 include a greater outer diameter than the first stage planetary gears 220. In the illustrated embodiment, the plurality of second stage planetary gears 260 includes three second stage planetary gears 260. In other embodiments, the plurality of second stage planetary gears 260 can include fewer or more than three second stage planetary gears 260. The illustrated second stage planetary gears 260 are rotatably supported within slots 265 formed in an outer surface 270 of the housing 85. In particular, each second stage planetary gear 260 is rotatably coupled to the housing 85 by a second pin 275 and second planetary roller bearings 280 positioned between the second stage planetary gear 260 and the second

pin 275. The second pins 275 are fixed to the housing 85. In other embodiments, each second stage planetary gear 260 can be fixed relative to the corresponding second pin 275 and the second pins 275 can be rotatably coupled to the housing 85 by the second planetary roller bearings 280. The second stage planetary gears 260 engage a second ring gear 285.

With reference to FIG. 7, the first ring gear 240 and the second ring gear 285 are fixed to a first ring spacer 290 and a second ring spacer 295 to form the drum 90. The first ring spacer 290 and the second ring spacer 295 rotatably support the drum 90 relative to the housing 85. In particular, a first drum roller bearing 300 is positioned between the first ring spacer 290, the housing 85, and a drum bearing retainer 305. The drum bearing retainer 305 is fixed to a front surface 310 (FIG. 4) of the housing 85. A second drum roller bearing 315 is positioned between the second ring spacer 295 and the housing 85. With continued reference to FIG. 7, an end ring 320 is fixed to the second ring spacer 295 to interface with a seal ring 325. The seal ring 325 is fixed to the housing 85 and inhibits dirt and debris from entering between the drum 90 and the housing 85. In some embodiments, outer surfaces 330 of the first ring gear 240, the second ring gear 285, the first ring spacer 290, and the second ring spacer 295 provide a surface to which the plurality of cutting bit assemblies 100 are coupled.

As shown in FIG. 8, a portion of a longwall mining system 335 is illustrated including the shearer 10, a conveyor assembly 340, and roof supports 345 that are supported on a mine floor 350. The illustrated roof supports 345 are operable to advance the shearer 10 and the conveyor assembly 340 in a forward direction 355 toward a mine face 360. In the illustrated embodiment, the forward direction 355 is perpendicular to the first tramping direction 40 and the second tramping direction 45 of the shearer 10. Each roof support 345 is positioned behind the conveyor assembly 340 (i.e., away from the mine face 360) and includes a shield 365 extending over the chassis 20 and the conveyor assembly 340 to engage a mine roof 370 opposite the mine floor 350.

In operation, the first and second cutting assemblies 15 are moved about the first axis 25 to position the drums 90 of each assembly 15 relative to the mine face 360. For example, the first cutting assembly 15 can be elevated to cut material (e.g., coal or other minerals) from an upper portion of the mine face 360 adjacent the roof 370, while the second cutting assembly 15 can be lowered to cut material from a lower portion of the mine face 360 adjacent the floor 350. Referring again to FIGS. 1 and 7, the power unit 30 on the chassis 20 provides power to the motors 125 that rotate in unison to drive the corresponding output pinion 140. In turn, the output pinions 140 drive the sun gear 180 to rotate the drive shaft 200 about the rotational axis 95. The drive shaft 200 then drives the first stage planetary gears 220 about their corresponding first pin 230 to rotate the carrier 225. The compound gear 245 rotates with the carrier 225 about the rotational axis 95 to drive the second stage planetary gears 260 about their corresponding second pin 275. Ultimately, the first stage planetary gears 220 drive the first ring gear 240 and the second stage planetary gears 260 drive the second ring gear 285 to rotate the cutting bit assemblies 100 about the rotational axis 95 to cut material from the mine face 360. The cut material is then deposited on the conveyor assembly 340, and the conveyor assembly 340 moves the cut material away from the mine face 360. While the first and second cutting assemblies 15 are cutting material from the mine face 360, the shearer 10 trams along the track 35 in the

first direction 40 or the second direction 45. Accordingly, with each pass of the shearer 10 along the mine face 360 in the first direction 40 or the second direction 45, a section of material 375 is cut from the mine face 360 (FIG. 8).

5 In the illustrated embodiment, the powertrain 80 includes a plurality of motors 125 that rotate the drum 90 about the rotational axis 95 through two planetary stages to provide torque to exert a cutting force to cut material from the mine face 360. In other embodiments, the powertrain 80 can be 10 configured differently but still provide torque to exert a cutting force to cut material from the mine face 360. For example, the powertrain 80 can include fewer or more than three motors 125 and/or fewer or more than two planetary stages.

15 FIGS. 9-14 illustrate a cutting assembly 15a according to another embodiment. The cutting assembly 15a is similar to the cutting assembly 15; therefore, similar components are designated with similar reference numbers and include the letter "a." At least some differences and/or at least some 20 similarities between the cutting assemblies 15, 15a will be discussed in detail below. In addition, components or features described with respect to the cutting assembly 15a can be similarly applicable to any other embodiments described herein.

25 With reference to FIGS. 9 and 10, a support structure 60a includes a base 380a that is pivotably coupled to a chassis mount 50a about a second axis 385a. The second axis 385a is perpendicular to a first axis 25a. In other embodiments, the second axis 385a can be obliquely oriented relative to the 30 first axis 25a. As shown in FIG. 9, a first hydraulic actuator 390a is coupled to the chassis mount 50a and the base 380a and is operable to pivot the support structure 60a and a drum and motor assembly 55a relative to the chassis mount 50a within a first angular range 395a. In the illustrated embodiment, the first angular range 395a is about 10 degrees. In other embodiments, the first angular range 395a can be less than 20 degrees, 30 degrees, 40 degrees, etc. The first 35 hydraulic actuator 390a is operable by the power unit 30.

With continued reference to FIGS. 9 and 10, the illustrated support structure 60a also includes a structural member 75a pivotably coupled to the base 380a. In particular, the structural member 75a is pivotably coupled to the base 380a about a third axis 400a that is perpendicular to the second axis 385a. In addition, the structural member 75a is pivotably coupled to a housing 85a of the drum and motor assembly 55a about a fourth axis 405a. The fourth axis 405a is perpendicular to a longitudinal axis 410a of the structural member 75a, which extends between the third and fourth axes 400a, 405a. As shown in FIG. 9, a second hydraulic actuator 415a is coupled to the base 380a and the housing 85a and is operable to pivot the structural member 75a and the drum and motor assembly 55a about the third axis 400a relative to the base 380a within a second angular range 420a. In the illustrated embodiment, the second angular range 420a is about 15 degrees. In other embodiments, the second angular range 420a can be between about 0 degrees and about 10 degrees, between about 0 degrees and about 20 degrees, between about 0 degrees and about 30 degrees, between about 0 degrees and about 40 degrees, etc. The 50 second hydraulic actuator 415a is powered by the power unit 30.

In addition, as shown in FIG. 9, a third hydraulic actuator 425a is coupled to the structural member 75a and the housing 85a. The third hydraulic actuator 425a is operable 55 to pivot the drum and motor assembly 55a about the fourth axis 405a relative to the support structure 60a within a third angular range 430a. In the illustrated embodiment, the third

angular range **430a** is about 15 degrees. In other embodiments, the third angular range **430a** can be between about 0 degrees and about 10 degrees, between about 0 degrees and about 20 degrees, between about 0 degrees and about 30 degrees, between about 0 degrees and about 40 degrees, etc. The third hydraulic actuator **425a** is operable by the power unit **30**.

In operation, the drum and motor assembly **55a** rotates about a rotational axis **95a** for cutting bit assemblies **100a** to cut material from the mine face **360**. The drum and motor assembly **55a** can also move about the first axis **25a**, move about the second axis **385a** within the first angular range **395a**, move about the third axis **400a** within the second angular range **420a**, and move about the fourth axis **405a** within the third angular range **430a**. Accordingly, the drum and motor assembly **55a** includes five degrees of movement and can simultaneously or independently move in any combination of the five degrees of movement. In other embodiments, the drum and motor assembly **55a** can include at least three degrees of movement (e.g., movement about the first axis **25a**, movement about the rotational axis **95a**, and movement within one of the first angular range **395a**, within the second angular range **420a**, or within the third angular range **430a**). That is, it is understood that the drum and motor assembly **55a** may be constructed with one or two of the three points of articulation illustrated at axis **385a**, **400a**, and **405a**.

With reference to FIG. 11, the rotational axis **95a** of the drum and motor assembly **55a** can move in an upward tilt direction **435a** or a downward tilt direction **440a** within the first angular range **395a**. Accordingly, the cutting assembly **15a** can shape the mine face **360** relative to the mine floor **350**. For example, in some situations the mine floor **350** and the mine face **360** may not be perpendicular to each other as shown in FIG. 8. As such, the drum and motor assembly **55a** can move in the tilt directions **435a**, **440a** to ensure the mine face **360** is perpendicular to the forward direction **355** and/or the mine floor **350** as the shearer **10** moves in the first direction **40** or the second direction **45**.

With reference to FIG. 12, the rotational axis **95a** of the drum and motor assembly **55a** is movable about the third axis **400a** in a first swing direction **445a** or a second swing direction **450a** within the second angular range **420a**. In addition, with reference to FIG. 13, the rotational axis **95a** of the drum and motor assembly **55a** is movable about the fourth axis **405a** in the first swing direction **445a** or the second swing direction **450a** within the third angular range **430a**. Accordingly, the drum and motor assembly **55a** can cut into the mine face **360** in the forward direction **355** while maintaining the rotational axis **95a** of the drum and motor assembly **55a** perpendicular to the mine face **360** (FIG. 13), without the roof supports **345** pushing the shearer **10** in the forward direction **355**. In particular, the drum and motor assembly **55a** is extendable in the forward direction **355** by a distance **455a** relative to the chassis **20** while maintaining the rotational axis **95a** of the drum and motor assembly **55a** perpendicular to the mine face **360**. In the illustrated embodiment, the distance **455a** is between 300 millimeters and 400 millimeters (e.g., 324 millimeters).

Accordingly, the illustrated shearer **10** can adjust an orientation of the drum and motor assembly **55a** while the shearer **10** is moving in the first direction **40**, the second direction **45**, and/or the forward direction **355**. Adjusting the orientation of the drum and motor assembly **55a** provides greater control of material being cut from the mine face **360**. For example, during operation, the track **35** along which the mining machine **10** trams may deviate relative to the direc-

tion of advance causing the mining machine **10** to move off of a desired cutting path. Such deviation may cause the mining machine **10** to cut the mine face **360** in an undesirable manner (e.g., nonlinearly as shown in FIG. 14). The illustrated cutting assembly **15a** can be adjusted to cut material to a desired linear line **460a** from the mine face **360** while the shearer **10** moves in the first direction **40**, the second direction **45**, and/or the forward direction **355**. In particular, the cutting assembly **15a** can be adjusted to account for deviations of the mining machine **10** during operation. The adjustability of the cutting assembly **15a** within the first, second, and third angular ranges **395a**, **420a**, **430a** also inhibits overloading the cutting bit assemblies **100a** by controlling a depth of the section **375** being cut from the mine face **360**.

FIGS. 15-19 illustrate a cutting assembly **15b** according to another embodiment. The cutting assembly **15b** is similar to the cutting assemblies **15**, **15a**; therefore, similar components are designated with similar references numbers and include the letter "b.". At least some differences and/or at least some similarities between the cutting assemblies **15**, **15a**, **15b** will be discussed in detail below. In addition, components or features described with respect to the cutting assembly **15b** can be similarly applicable to any other embodiments described herein.

With reference to FIGS. 15 and 16, a support structure **60b** includes a structural member **75b** that is slidably coupled to a chassis mount **50b** in a direction parallel to a first axis **25b**. With reference to FIG. 17, an interface between the support structure **60b** and the chassis mount **50b** includes a dovetail slider configuration. In particular, a slider **465b** is fixed to the chassis mount **50b** with protrusions **470b** of the structural member **75b** gripping the slider **465b** allowing the structural member **75b** to slide relative to the chassis mount **50b**. In other embodiments, the slider **465b** can be coupled to the structural member **75b** and the protrusions **470b** can be coupled to the chassis mount **50b**. With reference back to FIGS. 15 and 16, a first hydraulic actuator **390b** is coupled to a bracket **475b** of the chassis mount **50b** and the structural member **75b**. The bracket **475b** is received within a slot **480b** of the structural member **75b**. The first hydraulic actuator **390b** is operable to translate the support structure **60b** and a drum and motor assembly **55b** relative to the chassis mount **50b** within a first translational range or distance **485b** (FIG. 18). In the illustrated embodiment, the first translational distance **485b** is between about 100 millimeters and about 200 millimeters (e.g., about 165 millimeters). In other embodiments, the first translational distance **485b** can be less than 500 millimeters.

With reference to FIG. 16, a second hydraulic actuator **415b** is positioned within the structural member **75b** (e.g., a hollow structural member) to be coupled between the structural member **75b** and an arm **490b** of a housing **85b**. The arm **490b** is received within the structural member **75b** (e.g., the structural member **75b** is a sleeve to the arm **490b**). The second hydraulic actuator **415b** is operable to translate the drum and motor assembly **55b** relative to the structural member **75b** in a direction parallel to a longitudinal axis **410b** of the structural member **75b** within a second translational range or distance **495b** (FIG. 19). The longitudinal axis **410b** is perpendicular to the first axis **25b**. In the illustrated embodiment, the second translational distance **495b** is between about 300 millimeters and about 700 millimeters (e.g., about 499 millimeters). In other embodiments, the second translational distance **495b** can be less than 1000 millimeters.

In operation, the drum and motor assembly 55b rotates about a rotational axis 95b for cutting bit assemblies 100b to cut material from the mine face 360. The drum and motor assembly 55b can also move about the first axis 25b, move along the first axis 25b within the first translational range 485b, and move along the longitudinal axis 410b within the second translational range 495b. Accordingly, the drum and motor assembly 55b includes four degrees of movement while cutting bit assemblies 100b cut into the mine face 360. In other embodiments, the drum and motor assembly 55b can include at least three degrees of movement (e.g., movement about the first axis 25b, movement about the rotational axis 95b, and movement within the first translational range 485b or the second translational range 495b).

FIGS. 20-23 illustrate a cutting assembly 15c according to another embodiment. The cutting assembly 15c is similar to the cutting assemblies 15, 15a, 15b; therefore, similar components are designated with similar references numbers and include the letter "c." At least some differences and/or at least some similarities between the cutting assemblies 15, 15a, 15b, 15c will be discussed in detail below. In addition, components or features described with respect to the cutting assembly 15c can be similarly applicable to any other embodiments described herein.

With reference to FIGS. 20 and 21, a support structure 60c includes a structural member 75c that is slidably coupled to a chassis mount 50c in a direction parallel to a first axis 25c. An interface between the support structure 60c and the chassis mount 50c includes a dovetail slider configuration, as described above. A first hydraulic actuator 390c is coupled to a bracket 475c of the chassis mount 50c and the structural member 75c. The bracket 475c is received within a slot 480c of the structural member 75c. The first hydraulic actuator 390c is operable to translate the support structure 60c and a drum and motor assembly 55c relative to the chassis mount 50c within a translational range or distance 485c (FIG. 22).

As shown in FIG. 21, a second hydraulic actuator 415c is coupled to the structural member 75c and a housing 85c. The drum and motor assembly 55c is pivotably coupled to the structural member 75c about a fourth axis 405c. The fourth axis 405c is parallel to the first axis 25a. The second hydraulic actuator 415c is operable to rotate the drum and motor assembly 55c relative to the structural member 75c within an angular range 500c (FIG. 23). In the illustrated embodiment, the angular range 500c is between about 10 degrees and about 30 degree (e.g., about 20 degrees). In other embodiments, the angular range 500c can be less than 50 degrees.

In operation, the drum and motor assembly 55c rotates about a rotational axis 95c for cutting bit assemblies 100c to cut material from the mine face 360. The drum and motor assembly 55c can also move about the first axis 25c, move along the first axis 25c within the translational range 485c, and move about the fourth axis 405c within the angular range 500c. Accordingly, the drum and motor assembly 55 includes four degrees of movement. In other embodiments, the drum and motor assembly 55c can include at least three degrees of movement (e.g., movement about the first axis 25c, movement about the rotational axis 95c, and movement within the translational range 485c or within the angular range 500c).

FIGS. 24 and 25 illustrate a drum and motor assembly 55d according to another embodiment. The drum and motor assembly 55d is similar to the drum and motor assembly 55; therefore, similar components are designated with similar references numbers and including the letter "d." At least

some differences and/or at least some similarities between the drum and motor assemblies 55, 55d will be discussed in detail below. Additionally, any of the cutting assemblies 15, 15a, 15b, 15c discussed above can include the drum and motor assembly 55d.

The drum and motor assembly 55d includes a powertrain 80d supported by a housing 85d and operable to drive a drum 90d about a rotational axis 95d. The illustrated housing 85d supports a single motor 125d (e.g., an electric motor, a hydraulic motor, etc.). In the illustrated embodiment, the powertrain 80d is a four-stage planetary gear train. In other embodiments, the powertrain 80d can include fewer than four planetary stages or more than four planetary stages.

In particular, the motor 125d is coupled to an output pinion 140d that is rotatable about the rotational axis 95d. The output pinion 140d engages a plurality of first stage planetary gears 220d that are coupled to the housing 85d by first pins 230d. In particular, the first stage planetary gears 220d are rotatable about their corresponding first pin 230d via bearings, and the first pins 230d are rotatably fixed about the rotational axis 95d. In addition, the first stage planetary gears 220d are engaged with a first ring gear 502d. The first ring gear 502d is rotatable about the rotational axis 95d.

A plurality of second stage planetary gears 260d are coupled together by a second stage carrier 505d such that the second stage planetary gears 260d and the second stage carrier 505d are rotatable about the rotational axis 95d. The plurality of second stage planetary gears 260d engage the first ring gear 502d and a first portion 240d of the drum 90d. In the illustrated embodiment, the first stage planetary gears 220d and the second stage planetary gears 260d are aligned in a radial direction along the rotational axis 95d. In other embodiments, however, the first stage planetary gears 220d and the second stage planetary gears 260d can be offset along the rotational axis 95d (e.g., a ring gear spans between the first stage planetary gears 220d and the second stage planetary gears 260d). The second stage carrier 505d includes a third stage ring gear portion 510d that engages a plurality of third stage planetary gears 515d. The third stage planetary gears 515d also engage a second portion 285d of the drum 90d. The plurality of third stage planetary gears 515d are coupled together by a third stage carrier 520d such that the third stage planetary gears 515d and the third stage carrier 520d are rotatable about the rotational axis 95d. The third stage carrier 520d includes a fourth stage ring gear portion 525d that engages a plurality of fourth stage planetary gears 530d. The fourth stage planetary gears 530d also engage a third portion 535d of the drum 90d. The plurality of fourth stage planetary gears 530d are coupled together by a fourth stage carrier 540d, and the fourth stage carrier 540d is rotatably fixed about the rotational axis 95d. In particular, the fourth stage planetary gears 530d are rotatable about a corresponding second pin 275d coupled to the fourth stage carrier 540d, and the second pins 275d are rotatably fixed about the rotational axis 95d. As such, the fourth stage planetary gears 530d are also rotatably fixed about the rotational axis 95d.

In operation, the motor 125d drives the output pinion 140d to drive the first stage planetary gears 220d about their respective first pin 230d. In turn, the first ring gear 502d rotates about the rotational axis 95d to drive the second stage planetary gears 260d. The second stage planetary gears 260d then rotate about the rotational axis 95d to also move the third stage ring gear portion 510d about the rotational axis 95d. The third stage ring gear portion 510d drives the third stage planetary gears 515d about the rotational axis 95, which also moves the fourth stage ring gear portion 525d

11

about the rotational axis 95. The fourth stage ring gear portion 525d then rotates the fourth stage planetary gears 530d about their respective second pin 275d. Accordingly, the drum 90d is driven about the rotational axis 95d via engagements of the second stage, third stage, and fourth stage planetary gears 260d, 515d, 530d and the portions 240d, 285d, 535d.

Although certain aspects have been described in detail with reference to certain preferred embodiments, variations and modifications exist within the scope and spirit of one or more independent aspects as described. Various features and advantages of the disclosure are set forth in the following claims.

The invention claimed is:

1. A cutting assembly for a mining machine, the cutting assembly comprising:

a mount configured to move about a first pivot axis relative to a chassis of the mining machine;

a ranging arm coupled to the mount, the ranging arm moveable relative to the mount along a first translational axis parallel to the first pivot axis; and

a cutting head including,

a housing coupled to the ranging arm, the housing moveable relative to the ranging arm along a second translational axis transverse to the first translational axis,

a drum supported for rotation relative to the housing about a rotational axis,

a plurality of cutting bits coupled to the drum, and at least one motor supported by the housing to drive the drum about the rotational axis.

2. The cutting assembly of claim 1, wherein the cutting head includes at least two motors supported by the housing.

3. The cutting assembly of claim 2, wherein the housing supports at least a two-stage planetary transmission between the at least two motors and the drum to drive the drum about the rotational axis.

4. The cutting assembly of claim 1, wherein the cutting head includes at least a four-stage transmission coupled between the at least one motor and the drum to drive the drum about the rotational axis.

5. The cutting assembly of claim 1, wherein the ranging arm includes a plurality of hollow structural members.

6. The cutting assembly of claim 1, wherein the cutting head includes a single motor, wherein the housing supports at least a four-stage planetary transmission between the single motor and the drum to drive the drum about the rotational axis.

7. The cutting assembly of claim 1, wherein the cutting head includes three motors positioned within a cavity of the housing and oriented parallel to one another.

8. A cutting assembly for a mining machine, the cutting assembly comprising:

a mount configured to move about a first pivot axis relative to a chassis of the mining machine;

a cutting head including,

a housing,

a drum rotatably coupled to the housing about a rotational axis,

a plurality of cutting bits coupled to the drum, and at least one motor supported by the housing to drive the drum about the rotational axis; and

a ranging arm coupled to the mount and supporting the cutting head for movement about the first pivot axis, the

12

ranging arm moveable relative to the mount along a first translational axis, the first translational axis parallel to the first pivot axis, wherein the housing is moveable relative to the ranging arm about a second pivot axis, and wherein the second pivot axis is parallel to the first translational axis.

9. The cutting assembly of claim 8, wherein the ranging arm includes a plurality of hollow structural members.

10. The cutting assembly of claim 8, wherein the cutting head includes at least two motors supported by the housing.

11. The cutting assembly of claim 10, wherein the housing supports at least a two-stage planetary transmission between the at least two motors and the drum to drive the drum about the rotational axis.

12. The cutting assembly of claim 8, wherein the cutting head includes a single motor, wherein the housing supports at least a four-stage planetary transmission between the single motor and the drum to drive the drum about the rotational axis.

13. The cutting assembly of claim 8, wherein the cutting head includes three motors positioned within a cavity of the housing and oriented parallel to one another.

14. A cutting assembly for a mining machine, the cutting assembly comprising:

a ranging arm configured to be coupled to a chassis of the mining machine;

a cutting head including,

a housing coupled to the ranging arm,

a drum rotatably coupled to the housing about a rotational axis,

a plurality of cutting bits coupled to the drum, and at least one motor supported by the housing to drive the drum about the rotational axis; and

a mount coupled to the ranging arm, the mount configured to move about a first pivot axis relative to the chassis of the mining machine, the mount enabling movement of the drum about the first pivot axis,

wherein the drum is moveable along a first translational axis relative to the mount, wherein the first translational axis is defined between the ranging arm and the mount, wherein the drum is moveable along a second translational axis relative to the mount, wherein the second translational axis is defined between the ranging arm and the housing,

wherein the cutting assembly is configured to include at least four degrees of movement of the drum relative to the chassis.

15. The cutting assembly of claim 14, wherein the ranging arm includes a plurality of hollow structural members.

16. The cutting assembly of claim 14, wherein the cutting head includes at least two motors supported by the housing.

17. The cutting assembly of claim 14, wherein the cutting head includes three motors positioned within a cavity of the housing and oriented parallel to one another.

18. The cutting assembly of claim 17, wherein the housing supports at least a two-stage planetary transmission between the at least two motors and the drum to drive the drum about the rotational axis.

19. The cutting assembly of claim 14, wherein the cutting head includes a single motor, wherein the housing supports at least a four-stage planetary transmission between the single motor and the drum to drive the drum about the rotational axis.
